LOCK

Filed Nov. 3, 1923

Inventor:
Friedrich von Medem,
By Mark & Shan Attorneys

UNITED STATES PATENT OFFICE.

FRIEDRICH VON NIEDMANN, OF CHARLOTTENBURG, NEAR BERLIN, GERMANY.

LOCK.

Application filed November 3, 1923. Serial No. 672,502.

To all whom it may concern:

Be it known that I, FRIEDRICH VON NIEDMANN, a citizen of Russia, residing at Charlottenburg, near Berlin, in the State of Prussia, Germany, have invented certain new and useful Improvements in Locks; and I do hereby declare the following to be a full, clear, and exact description of the invention, such as will enable others skilled 5 in the art to which it appertains to make and use the same.

My invention relates to improvements in locks, and more particularly in locks of the type in which the bolt or hasp is operated 15 by means of a barrel mounted within the lock case and adapted to be rotated by means of bits formed on the key after setting locking members carried by the barrel in non-locking position. The object of the improvements is to provide a lock which is 20 safe as against operation by non-authorized persons, which can not be opened by other means except the correct key, and which does not permit impressions to be taken for 25 making false keys. With this object in view my invention consists in constructing the locking members in the form of spring 30 pressed bell crank levers pivotally mounted within the rotary barrel of the lock the outer arms of which project beyond the circumference of the barrel into position 35 for being locked by suitable stops provided within the case of the lock, and the inner arms of which are in position for being acted upon by bits formed on the key for rocking 40 the outer arms inwardly and out of locking position.

For the purpose of explaining the invention an example embodying the same has 45 been shown in the accompanying drawings in which the same reference characters have been used in all the views to indicate corresponding parts. In said drawings,—

Fig. 1, is an elevation showing the lock 50 attached to a door,

Fig. 2, is a perspective view of the lock detached from the door and with the base plate removed, and looking into the lock.

Fig. 3, is a detail view showing the base 55 plate,

Fig. 3^a, is an elevation of the base plate looking from the left in Fig. 3,

Fig. 4, is a cross-section taken on the line 4—4 of Fig. 1 and looking in the direction 55 of the arrows,

Fig. 5, is an elevation of the lock looking from the right in Fig. 1,

Fig. 6, is an elevation of the lock with the base plate removed and looking from 60 the rear side,

Fig. 7, is a detail sectional view showing the hasp and the means for blocking the same in non-locking position, the section being taken on the line 7—7 of Fig. 4,

Fig. 8, is a longitudinal section on an enlarged scale showing the barrel and the locking members mounted thereon,

Fig. 9, shows the key,

Fig. 10, is a cross-section of the key and a part of one of the locking members passing 65 from non-locking into locking position,

Fig. 11, is a similar section showing the locking member in non-locking position,

Figs. 12 and 13, are detail views showing the other one of the locking members and 70 looking respectively from the right and left in Fig. 8, and

Figs. 14 and 15, are detail views showing the locking member illustrated in Figs. 10 and 11.

In the example shown in the drawings the lock comprises a case 2 open at the rear side, a base plate 25 secured to the open side of the case, and a hasp 4 mounted on a pivot bolt 3 and passing through slots made in 80 the side walls 5 and 6 of the case, one of said slots being shown at 11. To the base plate 25 a leaf spring 26 is secured which acts on the hasp 4 and tends to push the same downwardly and into engagement with 85 a staple 9. The hasp carries a knob 7 for operation thereof by hand from the inner side of the door, and it is adapted for engagement with the staple 9. For blocking the hasp in locking position a pawl 10 is 90 pivotally mounted on the staple 9 which is adapted to be rocked upwardly and with its hook shaped end 101 into engagement with the hasp.

In the locking position the hasp 4 bears 100 with its bottom edge on the bottom wall of the slot 11, and a locking pin 13 engages in a hole 131 made in the hasp 4. The pin 131 is guided in a sleeve 132 secured to the front wall 21 of the case, and it is acted 105 upon by a spring 12 tending to push the same into locking engagement with the hasp. To the pin an arm 15 is secured which is formed at its bottom end with a beveled face 14. The hasp can be lifted out of lock- 110

ing engagement with the staple 9 only after first retracting the pin 13 by mechanism to be described hereafter.

Means are provided for holding the hasp 4 out of locking engagement with the staple 9. As shown a plate 17 is slideable in a recess 16 of the side wall 5, which plate carries a cranked arm 18 projecting through a slot 181 made in the wall 5. The plate 17 is normally pressed to the right in Fig. 5 by a spring 19. When opening the lock and rocking the hasp upwardly the plate 17 is pressed by the spring 19 in a direction towards the door and below the hasp 4, which is thereby prevented from falling downwardly and on the bottom wall of the slot 11. In this position of the hasp the hole 181 is out of position for engagement by the bolt 13, and the hasp can be lifted if desired. If however the door is closed the cranked arm 18 strikes on the front face of the base plate 91 of the staple 9, so that the plate 17 is shifted rearwardly against the action of the spring 19 and away from the hasp. Therefore the latter is free to drop into locking position, and the bolt 13 is shifted by the spring 12 into the hole 181 for locking the hasp. Now the lock can be opened from without only by means of the key. For opening the lock from within the bolt is retracted by means of a button 22 carried thereby and located outside the plate 23 of the case 2.

For lifting the hasp 4 out of engagement with the staple 9 a barrel is provided, which is rotatably mounted with its end portions 27 and 28 in sleeves 23 and 24 carried respectively by the plates 21 and 25. The said barrel shows an axial bore 29 adapted to receive the key 31, a pin 30 being axially mounted within said bore and corresponding to an axial bore of the key. The wall of the bore 29 is provided with lugs corresponding to notches of the keys, which lugs and notches are varied in different locks, as is known in the art.

Furthermore the barrel shows a prismatic portion 32 projecting laterally therefrom and disposed between stop plates 33 and 34 secured to the base plate 25, and an arm 35 located in position for engagement with the beveled face 14 of the arm 15 of the pin 13, so that when turning the barrel 27, 28 the pin 13 is shifted out of locking engagement with the hasp 4, which is therefore free to be lifted by the arm 35.

The locking members of the barrel consist of bell crank levers 36 and 39 mounted respectively on pins 37 and 38 secured to the wall of the portion 32 and acted upon by coiled springs 38 and 41 tending to push the levers with their outer arms out of the portion 32, as is shown in Fig. 8. The outer arm of the lever 36 is recessed as is shown at 361 in Figs. 12 and 13, and the said recess

is engaged by the outer arm of the lever 42, as is shown in Fig. 8. As appears from Fig. 6 the outer ends of the levers are disposed between shoulders 43 and 44 of the plates 33 and 34, so that in the projected position of the levers the barrel can not be turned by the key.

The levers 36 and 42 are adapted to be retracted out of locking position by inserting and turning the key. The inner arm of the lever 39 is formed with a circular cam face 45 engaging in a groove 46 of the key 31. Therefore when turning the key its cylindrical portion engages the cam face 45 so as to force the same to the left in Fig. 8, and to rock the lever 39 with its outer part 42 into the portion 32. Simultaneously a lug 47 provided at the end of the key engages the inner arm 40 of the lever 36 so as to force the same to the left in Fig. 8 and to rock the lever 36 with its outer arm into the portion 32, whereupon the barrel 27, 28 is free to be turned between the stops 33 and 34.

In order to make the levers 36 and 39 accessible by false keys, pick-locks and the like a partition wall 49 is provided between the said levers, which wall extends inwardly to the pin 30. The shaft of the key is provided with a corresponding recess 50 the breadth of which corresponds to the thickness of the wall 49, so that the key may be turned with its outer end and its main portion located at opposite sides of the partition 49.

While in describing the invention reference has been made to a particular example embodying the same I wish it to be understood that my invention is not limited to the construction shown in the drawings, and that various changes may be made in the general arrangement of the lock and the construction of its parts without departing from the invention.

I claim:

1. In a lock, the combination, with the locking member, of a barrel adapted to move said member and to receive and be turned by a key, a stop, a key formed with a longitudinal recess, and an elbow lever rockingly mounted within said barrel and normally projecting out of the same into position for locking engagement with said stop and having an inner cam face engaging in said recess of the key and adapted when turning the key to slide on the circumference thereof for retracting the lever out of locking engagement with said stop.

2. In a lock, the combination, with the locking member, of a barrel adapted to move said member and to receive and be turned by a key, a stop, a key formed with a recess and a cam face, and two rockable levers within said member on independent pivots and normally projecting out of the

same into position for locking engagement with said stop, one of said levers having an inner cam face in position for engagement with said recess and adapted when 5 turning the key to slide on the circumference thereof for retracting the lever out of locking engagement with said stop, and the other one of said levers being in position for engagement with said cam for being re- 10 tracted thereby out of locking position upon rotation of the key.

3. In a lock, the combination, with the locking member, of a barrel adapted to move said member and to receive and be turned 15 by a key, a stop, and a plurality of levers rockingly mounted on independent pivots

within said barrel on separate pivot bolts and normally projecting out of the same into position for locking engagement with said stop and each having a part located in 20 position for engagement by the key passed into the barrel and for being rocked thereby out of locking engagement with said stop, said barrel being provided with a partition wall intermediate said levers. 25

In testimony whereof I hereunto affix my signature in the presence of two witnesses.

FRIEDRICH VON NIEDMANN.
